Primary Examiner — Ruth McInroy(74) *Attorney, Agent, or Firm* — Grossman Tucker Perreault & Pfleger, PLLC(57) **CLAIM**

The ornamental design for a vacuum cleaner, as shown and described.

DESCRIPTION

FIG. 1 is a perspective view of a vacuum cleaner showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1; and,

FIG. 6 is a top plan view of FIG. 1.

The broken lines in the drawings are for illustrative purposes only and form no part of the claimed design.
